UNITED STATES PATENT OFFICE.

CHARLES E. MURRAY, OF CHICAGO, ILLINOIS.

CLOTH-SPONGING MACHINE.

Application filed May 18, 1921. Serial No. 470,546.

To all whom it may concern:

Be it known that I, CHARLES EDWARD MURRAY, a citizen of the United States of America, and a resident of Chicago, in the county of Cook, State of Illinois, have invented certain new and useful Improvements in Cloth-Sponging Machines, of which the following is a specification.

This invention relates to cloth sponging machines by which cloth or like fabric is dampened in the operation of shrinking the same previous to cutting and making into garments.

And this improvement has for its objects, To provide a structural formation and association of parts whereby the fabric undergoing the sponging operation is exposed to series of alternate dampening and squeezing operations in a continued passage through the machine to attain a very thorough dampening of the material without leaving any excess moisture therein as the fabric passes to the pleating or the reeling units of the machine.

To provide a structural combination of the parts and mechanisms whereby the reeling or the pleating of the fabric as it leaves the final squeezing rollers, can be readily shifted and directed to one or the other of the reeling or pleating units at the will of the operator, all as will hereinafter more fully appear.

In the accompanying drawings:—

Fig. 1, is a side elevation illustrating the general arrangement of parts in the preferred form of the machine.

Fig. 2, is an enlarged detail transverse section of the steam outlet ducts or pipes of the present improvement.

Fig. 3, is an enlarged detail longitudinal section of the steaming, dampening and squeezing units of the machine.

Fig. 4, is an end elevation of the operating mechanism of the reeling and pleating units of the machine.

Like reference numerals indicate like parts in the several views.

Referring to the drawings, 1 designates the supporting frame of the machine of any usual and suitable construction and provided with rails, standards and extensions adapted to support the different parts and mechanisms of the machine.

2 designates a semi-circular tank or casing arranged transversely of the frame 1 and having an open top covered by a horizontal apertured sheet or web 3 preferably of burlap fabric.

4 designates an inner pipe or duct extending longitudinally of the casing 2 and connected at one end with a source of steam supply. In the preferred construction the pipe 4 is formed with a single orifice or a plurality of orifices 4' in its top or crown and extending from end to end of the casing 2.

5 designates an outer pipe or duct encircling the inner pipe 4 and formed with an orifice or orifices 5' in its under side and extending from end to end of the casing 2. With such construction the annular space between the pipes 4, 5 forms very effective expansion chamber for the steam, and in connection with the central arrangement of the pipes with relation to the curved wall 75 of the casing 2 is adapted to attain an even distribution of the steam to the entire area of the orificed web or sheet 3 aforesaid.

6 designates the usual tension bars around which the fabric passes from a table 7 and overhead roller 8, to be properly tensioned in its movement in longitudinal contact with the orificed sheet or web 3 aforesaid. In such travel of the fabric over the sheet or web 3 it is exposed to the steam escaping 85 upwardly from the casing 2 to be moistened or dampened thereby.

9 designates a steeping tank arranged adjacent to the casing 2 and adapted to contain a body of water or other dampening fluid 90 and provided at one end with an overflow head 10 to maintain a constant fluid level in the tank under a continued supply of the water or like fluid.

11 designates an upper transverse roller 95 arranged at the side of the tank 9 adjacent to the casing 2 as shown. Such upper roller is adapted to deflect the cloth or fabric after it passes over the casing 2 downwardly through the fluid in the tank 9 to a bottom 100 roller 12 in said tank and from which said cloth or fabric passes upwardly to squeezing rollers as follows.

13 designates a pair of primary squeezing rollers journaled above the tank 9 at the 105 midlength of the same, and between which

the cloth or fabric passes and is effectively squeezed to remove any air particles which may remain in said cloth or fabric.

14 designates a bottom roller arranged 5 transversely in the tank 9 at the opposite side of the same from that in which the aforesaid roller 12 is arranged. The roller 14 is adapted to receive the cloth or fabric after its passage from the squeezing rollers 10 13 and down through the fluid in the tank 9 for a second immersion.

15 designates a pair of power driven squeezing rollers journalled in the frame 1 above the tank 9 and adapted to receive and 15 squeeze the cloth or fabric as it comes from the bottom roller 14 aforesaid.

The carrying shaft 16 of one of the rollers 15 is power driven and preferably constitutes the driving element by which the cloth 20 reeling and pleating mechanisms receive motion in unison with said squeezing rollers 15, as hereinafter described in detail.

17 designates an upright counter-balanced frame of the pendulum type, pivoted on top 25 rails of the main frame 1 by a transverse shaft 18 and formed with a lower forked end as shown in Fig. 1.

19 designates a pair of feeding rollers journalled in the forks of the lower end of 30 the frame 17, with the shaft of one of the rollers carrying a chain wheel 29.

21 designates a transverse countershaft also journalled on the aforesaid top rails of the main frame 1, in spaced relation to the 35 aforesaid shaft 18, and carrying at its respective ends cranks 22 connected by links 23 with the pendulum frame 17 to impart oscillatory movement to the same in the operation of the machine.

40 24 designates a chain or like belt operatively connecting chain wheels on the aforesaid shafts 16 and 21 to cause the same to rotate in unison.

25 designates a pair of idler chain or like 45 wheels loosely mounted on the aforesaid shaft 21, with one of said wheels operatively connected by a chain or like belt with a chain or like wheel 25' loosely mounted on the aforesaid drawing shaft 16. The other 50 of said wheels 25 is connected by a chain or like belt 27 with another pair of idler wheels as follows.

28 designates a pair of idler chain or like 55 wheels loosely mounted on the aforesaid shaft 18 and receiving motion from the chain or belt 27, above described, and which motion is in turn transmitted from one of the wheels 28 to a similar wheel 29 on the carrying shaft of one of the aforesaid feeding rollers 17, through a chain or belt connection 30, as shown in Fig. 1. With the described arrangement of parts a constant and positive feeding of the fabric operated on is attained during the oscillatory move-

ment of the pendulum frame 17 to lay the 65 fabric in pleats upon a receiving table 31.

32 designates an inclined track attached to an end of the main frame 1 and adapted to support an initially formed roll of the fabric undergoing treatment, with said core 70 or roll adapted to move by gravity into peripheral driven contact with a driving drum arranged as follows.

33 designates a transverse driving drum journalled in the frame 1 in separated relation to the main feeding and squeezing rollers 15 aforesaid, and operatively connected to a driving shaft thereof by a chain wheel and belt connection 33' as shown in Figs. 1 and 4. With such construction the described 80 core or roll of fabric receives peripheral motion from the driving drum 33 uniform with the feed of the fabric through the aforesaid main rollers 15, to attain a winding or reeling of the fabric into roll for convenient future handling, etc.

In the present construction, the pleating and the reeling mechanisms above described are intended for alternate use as required, and to such end the chain wheels 25' and 33' 90 above described are mounted loosely on the shaft 16 and have their opposed faces formed with clutch members which are alternately engaged by an intermediate movable clutch member 34 moving in a keyway 95 of the shaft 16, to impart positive rotation to the particular chain wheel with which the movable clutch member is engaged. Any usual operating means may be employed to shift the clutch member 34, and hold the 100 same to its engagement.

35 designates an idler drum journalled transversely in the aforesaid top rails of the main frame 1, and driven by a chain and wheel connection 36 with the aforesaid crank 105 shaft 21. Said drum 35 is adapted to receive the fabric as it comes from the main rollers 15 and guides the same in a proper manner to the feed rollers 19 of the pendulum frame 17 aforesaid in the active use of the same. 110

Having thus fully described my invention, what I claim as new and desire to secure by Letters Patent, is:—

1. In a sponging machine of the type described, the combination of a casing having 115 an open top, an orificed web arranged over said open top, means for feeding a fabric over and in contact with said web, a steam inlet duct arranged in said casing, a steeping tank arranged adjacent to said casing, 120 guiding rollers associated with said tank and adapted to direct the fabric through said tank, a pair of intermediate squeezing rollers associated with said tank, and a pair of power driven feeding and squeezing 125 rollers associated with said tank.

2. In a sponging machine of the type described, the combination of a casing having

an open top, an orificed web arranged over said open top, means for feeding a fabric over and in contact with said web, a steam inlet duct arranged in said casing, a steeping tank arranged adjacent to said casing, guiding rollers associated with said tank and adapted to direct the fabric through said tank, a pair of fabric feeding and squeezing rollers associated with said tank, individual

reeling and pleating mechanisms associated 10 with a shaft of said feeding and squeezing rollers, and a clutch mechanism mounted on said shaft and adapted for operative engagement with one or the other of said reeling or pleating mechanisms.

15

Signed at Chicago, Illinois, this 12th day of May, 1921.

CHARLES E. MURRAY.
